CLAIM

The ornamental design for an auto heat press machine, as shown and described.

DESCRIPTION

FIG. 1 is a front, top perspective view of an auto heat press machine, showing my new design;

FIG. 2 is a rear, bottom perspective view thereof;

FIG. 3 is a right, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The dashed broken lines in the figures are for the purposes of illustrating portions of the auto heat press machine, which form no part of the claimed design.

1 Claim, 9 Drawing Sheets
